LINK CHAIN FOR A BRACELET OR THE LIKE

Adolph Katz, Providence, R. I., assignor to Coro, Inc.,
New York, N. Y., a corporation of New York

Application August 17, 1955, Serial No. 37,509

Term of patent 7 years

(CL. D45—4)

Fig. 2

Fig. 1 is a plan view of a link chain for a bracelet or the like showing my new design.

Fig. 2 is an edge view thereof.

I claim:

The ornamental design for a link chain for a bracelet or the like, substantially as shown.
